UNITED STATES PATENT OFFICE.

FRANK MAGIDSON, OF PITTSBURGH, PENNSYLVANIA, ASSIGNOR TO PROGRESS TUBE COMPANY, A CORPORATION OF PENNSYLVANIA.

APPARATUS FOR MAKING METAL TUBING.

Application filed October 27, 1920, Serial No. 419,847. Renewed December 29, 1924.

To all whom it may concern:

Be it known that I, FRANK MAGIDSON, a citizen of the United States, and a resident of Pittsburgh, in the county of Allegheny and State of Pennsylvania, have made a new and useful Improvement in Apparatus for Making Metal Tubing, of which the following is a specification.

This invention relates to apparatus for making metal tubing and more especially to apparatus for making butted tubing or other hollow sections of any desired shape or cross-section from skelp or strip metal while in a cold state.

15 A further object is to provide apparatus whereby metal tubing of relatively light gage may be made at small cost.

A still further object is to provide apparatus whereby skelp or strip metal in a 20 single pass or operation may be converted into butted tubing of any desired cross section.

A still further object is to provide apparatus automatic in its operation and by 25 means of which reeled strip material may be fed and continuously converted into butted tubing of any desired shape and of the same gage as the metal strip.

These, as well as other objects which will 30 readily appear to those skilled in the metal tubing art, I attain by means of the apparatus described in the specification and illustrated in the drawings accompanying and forming part of this application and 35 throughout which similar elements are denoted by like characters.

The apparatus broadly consists of means for forcibly propelling a flat strip of metal longitudinally into and through forming 40 dies whereby it is transversely bent into tube form; in means for preventing buckling or distortion of the strip from the propelling means to the forming dies; and means for swaging the strip during its longitudinal movement and transverse bending 45 into finished form.

In the drawings, Figure 1 is a top plan view of apparatus embodying this invention. Fig. 2 is a view of the front or entering 50 end of the apparatus. Fig. 3 is a sectional view taken on line 3—3 of Fig. 1. Fig. 4 is a sectional view taken on line 4—4 of Fig. 1, looking in the direction of the arrows. Fig. 5 is a detail view of a portion 55 of the apparatus. Fig. 6 is an enlarged

fragmentary view of portions of the apparatus. Figs. 7, 8 and 9 are enlarged detail views of portions of the apparatus. Fig. 10 is a top plan view illustrating the progressive transverse bending of the strip around the mandrel. Figs. 11, 12, 13 and 14 are cross sectional views of the dies or wedges used for progressively bending the strip transversely into tube form and Figs. 15, 16 and 17 are cross sections of dies and 60 mandrels used in making tubing of various sections. These views illustrate the tubing within the closed portion of the die.

In describing my invention by aid of the views above referred to, I desire to point out that the same are merely illustrative of the apparatus as actually built and that I do not care to confine my invention to the precise construction and arrangement of parts shown. The following description is 70 therefore to be broadly construed as including suitable constructions and arrangement of parts which are obviously equivalent to those hereinafter referred to.

Strip propelling and guiding mechanism.

Cylindrical rolls 20 and 21 journaled in suitable bearings 22 and 23 mounted in end frames 24 and 25 as is now common in mill construction, are employed for propelling the strip material. Roll 21 is mounted in rigid bearing, while roll 20 is vertically adjustable to accommodate different thicknesses of skelp or strip material. The pressure on the strip exerted by the rolls is secured by means of adjusting screws 26, and rolls 20 and 21 are geared together by gears 27 and 28, so that both are driving rolls. As the skelp or strip material used does not vary much in thickness from the thinnest to the thickest gage, gears are chosen which will allow sufficient separation of the rolls to accommodate varying thicknesses of material. Roll 21 is driven from a suitable motor 29 through a train of gears 30, 31 and 32 and a worm 33 and worm-wheel 34 secured to the roll shaft.

A feed table 35 is provided at the entrance side of the rolls along which the skelp or strip material is guided to the rolls, and for guiding the strip to the center of the rolls, guides 36 adjustable laterally of the table are provided. These are mounted on a cross rod 37 and locked in adjustable positions thereon by set-screws 38.

The rolls 20 and 21 are each provided with a centrally located rectangular groove, the groove of roll 20 being numbered 39 and that of roll 21, 40. These grooves must be materially less in width than any strip that is to be used, as it is necessary to have the strip contact with sufficient roll surface on each side of the groove so that it may be forced through the dies.

- 10 Located on the leaving side of the feed rolls are two guides for the strip; one guide 41 is located below the strip while one 42 is located above the strip. Each of these guides is provided with an extension 43, 15 which extends into the groove of its roll to a point in front of meeting line of the rolls. Guide 41 is rigid and its upper surface is tangent to roll 21. Guide 42 is vertically adjustable and is locked in adjusted 20 position by means of a locking screw 44 which extends through a slot 45 in a support frame 46. Guide 42 is made adjustable to accommodate different thicknesses 25 of strip material and will be raised and lowered with roll 20, so that its lower face is always tangent to roll 20. Guides 41 and 42 prevent the strip from buckling and cause it to travel in a straight line to the die.

30 *Forming and swaging mechanism.*

The strip is forced through a forming die and around a mandrel located in the die and is swaged or pressed into finished 35 form during its travel through the die.

The die is sectional and is made up of two parts 47 and 48 of identical shape, and this will be so whenever tubing of symmetrical section is to be made. When 40 the die sections are in contact one with the other, they provide a through passage 49 of the same cross-section as the cross-section of the finished tube. The forward or entering face of the composite die is diagonally disposed with relation to the line 45 of movement of the strip passing between guides 41 and 42 and therefore diagonally to the major axis of passage 49.

Cutting away the entrance face of the 50 die diagonally to the line of travel of the strip presents a forming channel which increases in depth as it approaches the rear portion of the die or in other words, the walls of the die channel increase in height 55 from the forward end of the die to that point at which the walls meet to form the closed die passage. By means of these walls of progressively increasing height, the metal strip as it is forced through the die, 60 is simultaneously bent laterally or transversely in opposite directions with relation to its median line and this bending occurs in increments until the opposite edges of the strip arrive in proximity one to the 65 other at the top of the die passage.

If the tubing or other hollow article to be formed is of symmetrical contour, the channels in the die sections will be made so that the strip will be transversely bent equally on opposite sides of its median line, 70 so that the median line of the strip, the major axis of the tube and the tube seam will lie in one and the same plane.

A mandrel 51 having a forwardly extending support portion 52 above the open 75 end of the die passage, extends into the closed portion of the die passage and this portion in cross section is the same as the interior or bore of the finished tube.

Each die section is provided with a tenon 80 53 which fits within a hole formed for its reception in a cross head or slide 54. The die sections are clamped in place by means of clamp screws 55 each threaded through an arm 56 of a bracket 57 bolted to its 85 cross-head. The cross-heads are arranged to slide toward and from one another within guide ways 58 formed in a supporting member 59 bolted at 60 to the end members 90 of the apparatus.

Each of the cross-heads in its under portion is provided with a slot or channel 61 within which the upper bifurcated arm 62 of one of a pair of operating levers is adapted to be reciprocated. These levers 95 are pivotally mounted at 64 to the support member 59 and each lever is provided with a long arm 65 carrying an anti-friction roller 66 at its lower end.

A cam wheel 67 provided with tooth-like 100 portions 68 and hollows 69 is carried on a shaft 70 which lies between rollers 66. Shaft 70 at its forward end carries a pinion 71 which meshes with gear 31. Each of the cross-heads is connected up to the upper 105 arm of one of the operating levers and this connecting means consists of a rod 72 which extends through a hole 73 in the outer end of the cross-head and lies between the furcate parts of the upper arm of its lever. The inner end of the rod is provided with an enlarged head 74 which abuts against the inner side of the lever.

Two buffer devices, one carried by each 110 of the rods 72 abut against the outer ends 115 of the cross heads. Each buffer device comprises a rubber buffer element 75 which surrounds its rod 72. Each buffer element 75 is confined between end plates 76 and 77. Each buffer assembly is secured together by 120 means of bolts 78. The bolts also form means for initially compressing the buffer elements 75; rods 72 are threaded to receive nuts 79 and lock nuts 80.

The tooth portions 68 of cam wheel 67, 125 as the wheel rotates, cause the die sections to move into contact one with the other, and the hollows 69 between the tooth sections allow the die sections to be forced apart or the die opened, by the strip of 130

metal as it is forced between the sections. The buffer elements of the two rods 72 must be adjusted so that the cross heads will travel simultaneously and in the same amount to insure uniform swaging action of both die sections as to speed and intensity of blow. The buffers offer some resistance in case foreign matter enters the die.

10 A guide 81, bolted to support member 59, and axially alined with relation to the die passage 49 serves as a guide and support for the tubing as it issues from the die.

In a machine adjusted so as to feed skelp or strip metal at the rate of ten (10) feet per minute through the die, I have found that satisfactory results are obtained by reciprocating the die sections together 750 times per minute, or, in other words, closing 20 the die 750 times per minute.

It will be understood that the cam wheel for reciprocating the die sections can be driven independently of the rolls and by a separate motor, so that the periodicity of the 25 swaging operations may be varied to suit the particular material being worked on.

It will be seen that by progressively bending strip material laterally or transversely with relation to its median line and forming 30 the same in a sectional vibrating swaging die, tubing of any desired cross-section may be produced by a single operation or single pass.

As the strip is fed continuously, any suitable 35 means may be used for welding the seam of the tube as it issues from guide member 81 and any suitable means may be used for cutting the tubing to length. If it is made from skelp, the pieces leaving 40 the rolls may be pushed through the die by the next piece entering the rolls as the guides 41 and 42 will prevent the skelp from buckling.

In accordance with the provisions of the 45 Patent Statutes, I have described the principle of operation of my invention, together with one form of apparatus, but I desire to have it understood that the device shown is only illustrative and that the invention can 50 be carried out in other ways.

Having thus described my invention, what I claim as new and desire to secure by Letters Patent is:—

1. In apparatus for forming tubing, a 55 mandrel, means for longitudinally propelling strip material past said mandrel, dies mounted for reciprocation on opposite sides of said mandrel, and means for reciprocating said dies while the strip material is moving, whereby said material while forwardly moving is transversely bent on opposite sides of its median line around said mandrel and subjected to periodically applied pressure sufficient to swage-finish 60 the same.

2. In apparatus for forming tubing, a mandrel, rolls for propelling strip material longitudinally and past said mandrel, a longitudinally split die, the halves of which are mounted for reciprocation on opposite 70 sides of said mandrel, means for guiding the strip material from said rolls to said die, and means for reciprocating the sections of said die while the strip material is moving whereby the same, while moving, is transversely bent on opposite sides of its median line around said mandrel.

3. In apparatus for forming tubing, a mandrel, a transversely divided combined forming and swaging die, mounted for 80 co-operative reciprocation toward and from said mandrel, means for reciprocating the sections of said die at frequent intervals, means for guiding strip material to the entrance of said die and for preventing same 85 from buckling and rolls for forcing strip material through said die during its reciprocations.

4. In apparatus for forming tubing from skelp or other strip metal, means for longitudinally moving the material, and periodically reciprocating means for bending the material transversely on opposite sides of its median line and simultaneously with such bending for subjecting the bending material 90 to periodically applied transverse pressure sufficient to swage the same to finished 95 form.

5. In apparatus for forming butted tubing, guides for compelling strip material 100 passing therebetween to move in a straight line, feed rolls grooved so as to straddle said guides and propel strip material therebetween, a mandrel and means surrounding said mandrel for bending strip material transversely in opposite directions around 105 said mandrel, and means for subjecting that portion of the strip adjacent the mandrel to periodically applied transverse pressure during its longitudinal movement.

6. In apparatus for making tubing from strip metal, a die provided with a through passage and having its entrance opening located in a die face diagonally disposed to the major axis of said passage, a mandrel 115 supported adjacent the entrance of said die and extending into said passage, rolls for propelling flat metal strip through said die, and means for preventing the strip from buckling during its passage from said rolls 120 to said die.

7. In a machine for making tubing from strip metal, a longitudinally split die, a mandrel supported adjacent the entrance of said die and extending thereinto, means for feeding strip material into and through said die, and means operating in conjunction with said material to periodically reciprocate the portions of said die during the 125 passage of material therethrough.

8. In apparatus for forming hollow sections, a longitudinally split die formed for progressively bending material to finished form, a mandrel extending into said die 5 from its entrance side, rolls for forcing strip material through said die, guides located above and below the strip material and extending from a plane including the axes of said rolls to said die for preventing 10 the strip from buckling, and means for reciprocating the sections of said die towards said mandrel.
9. In apparatus for forming hollow sections, a longitudinally split die, a mandrel 15 supported in front of said die and extending thereinto, means for reciprocating the sections of said die towards said mandrel, rolls for feeding strip material past said mandrel and through said die, guides extending from said die into grooves in said rolls and past 20 the plane including the axes of said rolls for preventing strip material forced by said rolls through said dies from buckling between said rolls and said die.
10. In apparatus for forming hollow sections, strip feeding rolls provided with aligned circumferential grooves, swage dies for receiving and acting on strip material propelled by said rolls, and guides extending from said die into said grooves past the 25 plane including the axes of said rolls.

In testimony whereof, I have hereunto subscribed my name this 25th day of October, 1920.

FRANK MAGIDSON.
